PUMPING APPARATUS

Marshall E. Jennings, Michigan City, Ind., assignor to Sullivan Machinery Company, a corporation of Massachusetts

Application March 4, 1937, Serial No. 128,903

28 Claims. (Cl. 230—24)

My invention relates to pumping apparatus, and, more particularly, to unloading means for pumping apparatus.

In the unloading of pumping apparatus, and particularly in the unloading of air compressors, it is important that there be provided means which shall be positive in operation, quick in action, simple in construction, and not subject to easy derangement. It is also important that the unloading devices, particularly any which are to be associated with the valve mechanisms of the pumping apparatus, shall be very simple. Devices for opening and holding open the inlet valves of compressors to effect unloading are very common. Devices for effecting unloading by inter-connecting the opposite ends of the cylinders through the discharge connection of the pumping apparatus may also be used. With inlet valve opening unloading devices, interference 20 with flow of air to the inlet ports is frequently a difficulty, and substantial complication in structure at times results. To effect opening and maintaining open of discharge valves presents a substantial problem. If a device or system can be devised for opening and maintaining open either inlet valves or discharge valves—a pumping apparatus avoiding the complications and interferences with flow usually attending the use of inlet valve opening types of unloading apparatus—such a device or system would present a marked advantage; and I have devised a system which, in its broad aspects, is applicable either to hold open an inlet valve or a plurality of inlet valves, or a discharge valve or a plurality 30 of discharge valves, thereby to effect unloading with an absolute minimum of interference with freedom of flow of air relative to the pumping apparatus cylinder, and of great simplicity and effectiveness.

From one broad aspect of my invention, the same may be embodied either in conjunction with an inlet valve or in conjunction with a discharge valve, and may include means associated with the guard of the valve mechanism with which it is incorporated for producing a lower pressure at the face of the guard which checks the opening movement of the valve than prevails at the opposite or seating side of the valve when the latter is in open position. In the case of an inlet valve for a single stage compressor, where the pressure acting upon the seat side of the valve is atmospheric or substantially atmospheric in the open position of the valve, the provision of a vacuum in the guard will result in a very effective unloading operation. In the case of a dis-

charge valve, where the pressure on the seat surface of the valve corresponds in the open position of the valve to discharge pressure, a mere venting of the pressure from the back of the valve, at the face of the guard, will produce such a differential in pressure as to maintain the valve automatically in open position. My invention contemplates, therefore, the employment, for the maintaining in unloading position of either inlet or discharge valves, of pressure differences between the face of the valve adjacent the guard and the face of the valve towards the seat, however produced.

It is an object of my invention to provide an improved pump unloading apparatus. It is another object of my invention to provide an improved apparatus for effecting unloading which shall maintain in unloading-effecting position one of the valve devices of a pump, by means for subjecting the side thereof remote from its seat to a pressure lower than the pressure which prevails in the passage through which it controls flow. It is a further object of my invention to provide an improved apparatus for effecting unloading which shall cooperate with the inlet valve or valves of a pump, and, with a minimum interference with the air flow through the inlet ports, yet be certainly effective and maintain the valves open without risk of fluttering. It is another object of my invention to provide an improved vacuum-operated unloading means. It is still another object of my invention to provide an improved apparatus for effecting unloading, which shall cooperate with the discharge valve or valves of a pump while in no material way reducing the space for free discharge of fluid past the valve when the latter is in open position. It is a further object of my invention to provide an improved unloading means made effective by a pressure less than the pressure whose flow is controlled by the valve controlled by said unloading means. It is a still further object of my invention to provide an improved compressor discharge pressure responsive system for effecting unloading of a compressor, in which the actual valve holding forces shall be the result of the subjecting of the valve to a vacuum. It is yet another object of my invention to provide an improved apparatus for effecting compressor unloading according to which the valve element to be controlled is subjected directly to a pressure less than that which it controls, to bring about unloading, with a result that great simplification of construction is possible. Still another object of my invention is to provide a vacuum-operated

unloading device for holding in open position a pump unloading valve, holding said valve in such position during unloading that the same shall in no way interfere with or be subjected to any material closing force as a result of the flow of air through the inlet ports of the pumping apparatus of which said valve forms a part. Yet a further object is to provide unloading means associated with a discharge valve for a pump, of simple construction yet effective to relieve the valve when in unloading position from any closing tendency resulting from flow, in either direction past the same, of fluid moving towards and from the cylinder with which said valve is associated. Other objects and advantages of my invention will hereinafter more fully appear.

In the accompanying drawings, in which three illustrative embodiments of my invention have been shown.

20 Fig. 1 is a view partially in side elevation and partially in central vertical section through a single stage compressor in conjunction with which my invention is incorporated.

Fig. 2 is an enlarged detail section on a plane corresponding to the plane of Fig. 1, through an inlet and discharge valve mechanism at one end of a pump cylinder such as is shown in Fig. 1.

Fig. 3 is a face view of a valve guard used in the practice of my invention.

30 Fig. 4 is an enlarged fragmentary section on the plane of the line 4—4 of Fig. 3.

Fig. 5 is a fragmentary view showing portions of the inlet valve structure of Fig. 2, showing the parts in unloading condition.

Fig. 7 is a view on an enlarged scale showing portions of the structure shown in Fig. 1, but in elevation, as it were, showing a piping and valve layout of the unloading mechanism of Fig. 1.

Fig. 8 is a view, partially in section and partially diagrammatic, with parts on different scales, illustrating an embodiment of my invention in which the same is incorporated in the control of a pump discharge valve.

Fig. 9 shows a modified construction in which the invention is incorporated, in an illustrative embodiment, in a compound compressor.

50 From the foregoing statements it will be evident that my invention is capable, in different aspects, of incorporation in single-stage and in multi-stage pumping apparatus, in conjunction with inlet valves, or in conjunction with discharge valves. In Figs. 1 to 7 an embodiment in a single-stage double-acting compressor, in association with the inlet valves thereof, is shown. In Fig. 8 an embodiment in conjunction with one end of a pump cylinder, in conjunction with a discharge valve of that cylinder end, will be observed. In Fig. 9 an embodiment in a compound or two-stage pumping apparatus is disclosed.

is disclosed.

Referring first to Figs. 1 to 7 inclusive, it will be observed that an air compressor 1 having a driving pulley and fly wheel 2 supported upon a crank shaft 3 is provided with a piston 4 reciprocable in a cylinder 5 which comprises a central cylinder member 6 having a liner 7 and head and crank end cylinder heads 8 and 9 respectively. The compressor takes in air through an intake connection 10 which communicates with a passage 11 in the cylinder member 6, and with end intake chambers 12, 12, one in each of the heads 8 and 9. Inlet valve mechanism, of

which one is shown at each end of the cylinder, are generally designated 13; and discharge valve mechanisms, generally designated 14, control the discharge of air from the cylinder to a common discharge passage 15 from which the air is delivered through a pipe 16 to a point of use or storage, herein represented by a receiver 17.

Referring now to Fig. 2, it will be noted that the discharge valve mechanism 14 includes a seat element 20, to which there is suitably secured a guard member 21; and a valve 22 normally seats upon a seat 23 and controls the flow of fluid through passages 24 from the cylinder bore to the discharge space 15. A spring 25 normally holds the valve seated, and the valve and spring are guided by suitable guiding means 26. The discharge valve assembly is held in position by a stud 28 and a nut 29.

The inlet valve mechanism will be observed to be very similar in general appearance to conventional inlet valve mechanisms, and only by comparatively close inspection are its radical differences from the conventional inlet valve to be noted. It is held in position as a whole by a nut 30, threadedly engaging a reduced extension 31 of the stud 28, and comprises a seat element 32, a guard element 33, a guide element 34, an annular valve 35, and a spring 36 of the bowed or wave type, the several parts being held together by suitable machine screws or the like 31. 30

The guard 33 is somewhat thicker than the usual guard of this type, but this is simply an added advantage, for it tends to reduce the clearance volume of the cylinder. Referring first to Fig. 3, it may be observed that the side of the guard plate 33 towards the valve seat is provided with a series of grooves of progressively increasing depth and diminishing width. First there is a groove 40 of a radial width such as smoothly to receive the valve element 35. Next there is a slightly deeper groove 41 in which a vacuum is produced and maintained during unloading. Finally, there is a still deeper groove 42 which positions the seating spring 36, as will be noted in Fig. 2. The valve guard is provided with a radially extending passage 44 which communicates through passages 45 and 46 with the bottom of the groove 41 at opposite sides of the recess or groove 42 which serves to position and center the spring 36. The outer end of the radially extending passage is sealed, as at 47, while its inner end communicates with a port 48 in a conducting element 49, which takes the place of one of the screws 37, which act to hold the parts of the apparatus together. Now it will be evident, when it is noted that the depth of the groove 40 is sufficient to allow the valve element 35, when it is seated upon the annular surfaces 50^a and 50^b at the bottom of the groove 40, to be disposed wholly within the solid annulus, so-to-speak, of the guard member 33, that there will be no possibility of the flow between the space

be no possibility of the air between the space 12 and the cylinder bore effecting any tendency to close the valve 35. It will be noted that the groove 41 provides an ample space for the free withdrawal of the air completely around the circumference of the valve guard, and it will be noted that the groove 42 adequately centers the valve spring 36, and said spring may be compressed in such a manner as to allow the valve element 35 to rest upon the bottom of the groove 40 upon the surfaces 50^a and 50^b. 70

The inlet and discharge valve mechanisms are duplicated at the opposite ends of the cylinder.

Now, the system for producing a vacuum in 75

the groove 41 and for controlling the creation and breaking of such vacuum will be described with respect to the compressor 1. It will be noted that a vacuum pump 52 of any suitable form is driven, herein by a belt 53, from a pulley 54 on the crank shaft 3. The vacuum pump draws the air from a line 55, and the vacuum line 55 is connected by branch connections 56 and 57 to approximately the central points in control valve devices, designated 58—one of which is associated with each of the inlet valve mechanisms 13. Each mechanism 58 includes a central body portion 59 and a lower end portion 60, between which a diaphragm 61 is clamped. The central portion 59 has a bore 62 with which, between its ends, the connection 56 communicates. A valve element 63 is secured as at 64 to the diaphragm 61, and is adapted, in the position shown in Fig. 6, to shut off communication between the connection 56 and a connection 65 which is connected in any suitable way with the passage 44, heretofore mentioned. The valve mechanism 58 also includes an upper head 66; and this upper head of the valve mechanism 58 has an annular seat 67 through which a passage opens, leading to a vacuum breaker valve 68, which permits ingress of air but prevents its discharge. The valve 63 has connected to it, or formed integral with it, a head 69 which is adapted either to engage the seat 67 and prevent communication between the vacuum breaking connection and the connection 65, or to seat upon another seat 70 surrounding the upper end of the bore in which the valve 63 moves and cut off the communication between passages 56 and 65. This valve is but one illustration of any suitable three-way valve mechanism which may be controlled in accordance with compressor discharge pressure variations to connect the vacuum guard of the inlet valve mechanism at appropriate times with the source of vacuum and with the vacuum breaker. A suitable spring 71 normally forces the valve 63 to the position shown in Fig. 6, and a connection 72 is provided for subjecting the diaphragm 61 to a pressure sufficient to overcome the force exerted by the spring 71 and the force exerted by the pressure upon valve 63 tending to hold it in the position of Fig. 6, to move the valve 63 to its opposite position with its head 69 engaging seat 67.

Now referring to Figs. 1 and 7, it will be noted that a connection 75 leads from the receiver or compressor discharge line to a pilot valve 76, which may be of any usual or well known form, and which is operative to admit pressure to a line 77, when the compressor discharge pressure reaches a desired upper value, and to vent the pressure from the line 77 when the compressor discharge pressure falls off to a desired minimum value. The pilot valve shown at 76 is a well-known valve of commerce, a so-called RCS pilot valve. Connection 77 is branched, branch 77^a terminating in the connection 72 of one valve device 58, and branch 77^b leading to a corresponding connection associated with the other of the control devices 58, herein the one associated with the head-end unloading means.

The mode of operation of the apparatus so far described will be very easily followed. Let us assume that the receiver pressure rises to the maximum desired value, and that accordingly the pilot valve 76 acts to admit air through the connection 77 under receiver pressure. This air will act upon the diaphragms 61 and move the valves 63 to positions in which their heads 69

will engage their seats 67 and cut off communication between connections 65 and the vacuum breaker devices 68, while establishing communication between the connections 65 and the vacuum line 55 through the connections 56 and 57. Accordingly, a vacuum will be immediately produced in each of the grooves 41 associated with the inlet valves; and the inlet valves, upon their opening movements, will move back into the grooves 40 and be held there. So long as the vacuum is maintained in the grooves 41, the inlet valves will remain off their seats, in full-open position, the vacuum produced being more than sufficient to overcome the pressure of the springs 36. There will be no tendency of the inlet valves to be seated upon rush of air through the ports, as they will be shrouded, as it were, over their entire edge portions by the edges of the vacuum guard, and they will be subjected, moreover, at least to the inlet pressure of the compressor at all times on their seat sides, while subjected to a sub-atmospheric pressure on their other sides. When the receiver pressure has been reduced to the desired minimum value, valve 76 will vent the pressure from the line 77, and so the diaphragms 61 will be relieved of pressure on their lower sides, and valves 63 will be moved downward again to the position shown in Fig. 6. This will cut off communication between the vacuum guards and the vacuum producing device, and permit the breaking of the vacuum in the vacuum guards by air drawn in through the vacuum breaking devices 68. The passages connecting the vacuum guards with the valve devices 58 will be desirably made as short as possible.

Now with reference to Fig. 8, it will be observed that a compressor cylinder member 6' has associated therewith a head element 80 providing an inlet space 81, while the cylinder member 6' has a bore 82 and a discharge passage, of which a portion is shown at 83. Stepped bores 84 and 85 are formed in the cylinder head 80 and provide shoulders 86 and 87 against which a discharge valve mechanism 88 and an inlet valve mechanism 89 may be suitably clamped, with an intervening washer if desired, by means of a stud 90 and nuts respectively numbered 91 and 92. The inlet valve mechanism is of a conventional type, including a ported seat member 93 having flow passages 94 therein and concentric seats 95 and 96 engaged by an annular valve 97 which is held normally pressed against its seat by a spring 98 which also engages a guard 99, all as in a well known valve construction. The discharge valve mechanism 88 includes, herein, a conventional ported seat member 101 to which there is suitably secured a guide block 102 and a guard 103 by means of threaded elements, herein machine screws 104. A conventional annular valve 105 is designed to be held seated normally by a spring 106 of the annular, transversely flexed type. The valve guard 103 is provided with three concentric, progressively narrower, communicating grooves respectively numbered 107, 108 and 109. Groove 109 constitutes a guiding groove for the narrow annular bowed spring 106. Groove 108 is provided to enable free communication completely around the valve, when said valve is seated against the bottom of groove 107, said last mentioned groove being formed of a depth and width smoothly to receive the valve element 105.

Now, it will be evident that as the piston (not shown) reciprocates in the bore 82 of the cylinder on its suction strokes, it will cause unseating of 75

the valve 97 to take place and the flow of air into the cylinder. On the next succeeding opposite stroke of the piston, the valve 105 will be forced from its seat by the compressed fluid, and 5 will compress its spring 106 and ordinarily enter, at least partially, the groove 107. Upon the next succeeding suction stroke of the piston, the valve 105 will, of course, be seated again, during loaded operation of the pump.

10 If a pressure less than the discharge pressure of the compressor can be produced in any way within the groove 108, the discharge valve 105 will remain open, as soon as it once is fully opened, so long as such lowered pressure status 15 remains in the groove 108. With a discharge pressure of 75 or 100 pounds, it will be evident that a pressure not lower than atmospheric, created and maintained in the groove 108 will most effectively bring about and continue unloading, 20 by holding the discharge valve off its seat. No vacuum condition needs to be produced with a device of this character, where the valve opening pressures are considerably above atmospheric. Accordingly, unloading may be effected merely by 25 venting to atmosphere the pressure within the groove 108, when desired.

To illustrate one of many suitable devices for effecting the venting to atmosphere of the groove 108, I have shown a pressure-responsive switch 30 mechanism 111, comprising a diaphragm 112 subjected through a conduit 113 to compressor discharge pressure. The diaphragm 112 controls a bell-crank lever 114, which actuates a switch, diaphragmatically shown at 115. When the compressor discharge pressure reaches a desired maximum, the diaphragm 112, through the bell-crank lever 114, will open the switch 115. Upon a desired drop in pressure, to a value at which it is desired to effect reloading, the diaphragm 40 112 will move to a position permitting reclosing of the switch 115. Switch 115 controls a circuit including a conductor 116, a source of current 117, a conductor 118, a solenoid 119, and another conductor 120. When the switch is closed, the 45 solenoid 119 is energized. Solenoid 119 controls the position of a plunger 122 which controls the positions of a pair of oppositely facing valves 123 and 124 adapted selectively to cooperate with seats 125 and 126 respectively. When valve 124 50 is seated, it shuts off communication between a chamber 127 connected by a conduit 128 with the groove 108, and a further chamber 130 connected as at 131 to atmosphere. When valve 123 is seated, it cuts off communication between 55 the chamber 127 and a chamber 132, which is connected by a conduit 133 with the discharge space 83 of the compressor. When the solenoid 119 is de-energized, valve 123 is normally closed and valve 124 normally open.

60 The mode of operation of this illustrative construction will be readily followed. In the position of the parts shown, the compressor discharge pressure is at such a value that loaded operation of the compressor is desired. The switch 115 is 65 therefore closed, the solenoid 119 energized, valve 124 held seated, and valve 123 maintained unseated. Accordingly, the same pressure prevails in the groove 108 that prevails in the discharge space 83 and in the stepped bore 84, and accordingly the valve 105 operates in an entirely normal 70 manner. When the compressor discharge pressure increases, however, sufficiently to cause the diaphragm 112 to open the switch 115, the solenoid 119 will be de-energized, permitting the 75 plunger 122 to drop down to close the valve 123

and open the valve 124. The pressure in the groove 108 will immediately drop to atmospheric by way of conduit 128, chamber 127, port 126, chamber 130 and atmospheric vent 131; and the discharge valve 105 on its first opening movement 5 following the drop of pressure in the groove 108 will move fully into the groove 107 and be held there until reloading is desired. When the compressor discharge pressure falls off sufficiently to cause reclosing of switch 115, the solenoid 119 10 will be reenergized and valve 123 will reopen and valve 124 reclose, and the pressure in the groove 108 will equalize with that in chamber 83, and the discharge valve will resume normal functioning. Valves 123 and 124 may be interconnected, 15 or spring-loaded, to insure seating when desired.

In the embodiment of the invention shown in Fig. 9 there is simply provided an adaptation of the system of unloading shown in Figs. 1 to 7 to a compound compressor. Here it will be noted 20 that a common pilot valve 76' responsive through a connection 75' to the pressure in the receiver 17' controls through one branch 140^a of a forked connection 140 the flow to the valve devices 58^a, 58^a associated with the high pressure cylinder 141 25 of the compound compressor 1', while a branch 140^b of the forked connection 140 leads to the valve devices 58^b, 58^b controlling the unloading of the opposite ends of the low pressure cylinder 142 of the compound compressor 1'. In so far as the 30 apparatus associated with the low pressure cylinder is concerned, there is no essential difference from the apparatus shown in Figs. 1 to 7, a vacuum connection 65' being provided with a low-pressure-cylinder branch 55¹ for producing a 35 vacuum for use in unloading the low pressure cylinder through its inlet valves. The other branch, 55^b, of the vacuum connection leads to the devices 58^a, 58^a associated with the high pressure system. A delay in the unloading of the high 40 pressure cylinder is effected by employing a well-known arrangement, using a delay tank D with a suitably restricted flow line 143 limiting rate of flow through the delay tank to the devices 58^a, 58^a, and a check valve 144 permitting rapid 45 bleeding when reloading is desired. Check-valved connections 68' lead to the intercooler, instead of to the atmosphere, in the case of the high pressure devices 58^a.

Detailed description of the mode of operation 50 of this embodiment is unnecessary, as the low pressure cylinder unloading devices operate the same as the devices of Figs. 1 to 7, while the high pressure cylinder unloading devices are simply made effective subsequent to the low pressure 55 cylinder ones by the apparatus described, so that the intercooler pressure will be pumped down before complete unloading occurs.

It will be obvious that I have provided a very effective arrangement according to which a vacuum, or a pressure less than that which the valve controls, may be applied in a very convenient manner to effect compressor unloading, and may be applied to an inlet valve mechanism or to a discharge valve mechanism which will be little different in appearance and little more complicated than the ordinary construction without unloading means. It will be evident that the arrangement is simple, and certain in action, and that when unloading has been effected there is 70 no tendency during the passage of fluid back and forth between the cylinder bore and the space continuously placed in communication therewith for any fluid seating-pressures to act upon the valves.

While there are in this application specifically described three embodiments which my invention may assume in practice, it will be understood that these are shown for purposes of illustration and that the invention may be further modified and embodied in various other forms without departing from its spirit or the scope of the appended claims.

What I claim as new and desire to secure by Letters Patent is:

1. In a pump controlling system, a valve seat, a valve cooperating with said seat and movable to open position by a pressure-differential created during each cycle of loaded pump operation, and unloading means associated with said valve for subjecting its side more remote from said seat to a pressure less than the pressure which opens said valve to hold said valve open continuously, thereby to effect unloading.
2. In a pump controlling system, a cylinder, a piston, and valve mechanism including an inlet valve mechanism including a valve seat, a valve cooperating therewith and opened automatically by the pressure differential created on suction strokes of said piston during loaded pump operation, and unloading means associated with said valve for subjecting the side thereof remote from its seat to a vacuum to maintain said valve open during the discharge strokes of said piston.
3. In a pump controlling system, a cylinder, a piston, and valve mechanism including a discharge valve mechanism including a valve seat, a valve cooperating therewith and opened automatically by the pressure differential created on discharge strokes of said piston, and unloading means associated with said valve for subjecting the side thereof remote from its seat to less than discharge pressure to maintain said valve open during the suction strokes of said piston.
4. In combination, relatively movable pump elements cooperating to provide a pump chamber, valve devices associated with said pump chamber and automatically controlled during pumping by the pressure variations produced upon the relative movements between said elements and respectively serving as inlet and discharge control means for said chamber, and unloading means including means for subjecting one of said valve devices, upon the side thereof which, when said valve device is closed, is the more remote from said pump chamber, throughout the entire cycle of relative movements between said pump elements, to a pressure less than the pressure within said pump chamber, to hold said valve device open.
5. In combination, relatively movable pump elements cooperating to provide a pump chamber, valve devices associated with said pump chamber and automatically controlled during pumping by the pressure variations produced upon the relative movements between said elements and respectively serving as inlet and discharge control means for said chamber, and unloading means including means for subjecting one of said valve devices, upon the side thereof which, when said valve device is closed, is nearer said pump chamber, throughout the entire cycle of relative movements between said pump elements, to a pressure less than the pump intake pressure, to hold said valve device open.
6. In combination, relatively movable pump elements cooperating to provide a pump chamber, valve devices associated with said pump chamber and automatically controlled during pumping by the pressure variations produced
- upon the relative movements between said elements and respectively serving as inlet and discharge control means for said chamber and each having a seat towards and from which it is movable during opening and closing, and unloading means including means for subjecting one of said valve devices, upon the side thereof more remote from its seat, throughout the entire cycle of relative movements between said pump elements, to a pressure less than that at its other side, to hold said valve device open.
7. In an unloading system for a compound-compressor having a high pressure cylinder and a low pressure cylinder, each having a piston, and inlet and discharge valve mechanisms for said cylinders, said inlet valve mechanisms each including a valve seat, a valve cooperating therewith and opened automatically by the pressure differential created on suction strokes of the associated piston during loaded pump operation, and unloading means associated with each of said valves for subjecting the side thereof remote from its seat to a vacuum to maintain the same open to effect unloading.
8. In combination, a compound compressor having a high pressure cylinder and a low pressure cylinder, each having a piston, and inlet and discharge valve mechanisms for said cylinders, said inlet valve mechanisms each including a valve seat, a valve cooperating therewith and opened automatically by the pressure differentials created by piston movement in the cylinder which it serves during loaded operation, and unloading means associated with each of said valves for subjecting the side thereof remote from its seat to a pressure enough lower than that at its opposite side to maintain it open throughout both of the opposite piston strokes, to effect unloading.
9. In combination, a compound compressor having a high pressure cylinder and a low pressure cylinder, each having a piston, and inlet and discharge valve mechanisms for said cylinders, each of said valve mechanisms including a valve seat and a valve cooperating therewith and opened automatically by the pressure differentials created by the loaded operation of said compressor, and unloading means associated with corresponding valves on each cylinder for subjecting the sides thereof remote from their respective seats to pressures lower than those at their opposite sides to maintain said valves open to effect unloading.
10. In combination, a compound compressor having a high pressure cylinder and a low pressure cylinder, each having a piston, and inlet and discharge valve mechanisms for said cylinders, each of said valve mechanisms including a valve seat and a valve cooperating therewith and opened automatically by the pressure differentials created by the loaded operation of said compressor, and unloading means associated with a valve on each cylinder for subjecting the side thereof remote from its respective seat to a pressure lower than that at its opposite side to maintain said valves open to effect unloading.
11. In a pump controlling system, a pump having a valve associated with one end thereof and movable to open and close during each cycle of the pump end with which it is associated, and pump - discharge - pressure - controlled vacuum-governed unloading means associated with said valve for holding said valve open to effect unloading.
12. In a pump controlling system, a valve seat,

5 a valve cooperating with said valve seat and movable to open position by a pressure-differential created during each cycle of loaded pump operation, and unloading means associated with said valve and including means forming a chamber to receive said valve in its open position, said unloading means also including means for subjecting the side of said valve more remote from said seat continuously to a pressure less than the pressure which opens said valve, to hold said valve within said valve receiving chamber and so effect unloading.

10 13. In a pump controlling system, a cylinder, a piston, and valve mechanism including an inlet valve mechanism including a valve seat, a valve cooperating therewith and opened automatically by the pressure differential created on suction strokes of said piston, and unloading means associated with said valve and including a guard formed with a recess to receive said valve in its open position, said unloading means also including means for subjecting the side of said valve remote from its seat to a vacuum.

15 14. In a pump controlling system, a cylinder, a piston, and valve mechanism including a discharge valve mechanism including a valve seat, a valve cooperating therewith and opened automatically by the pressure differential created on discharge strokes of said piston, and unloading means associated with said valve for subjecting the side thereof remote from its seat to less than discharge pressure and for shielding the edges thereof from the flow of pressure fluid past the same.

20 15. In combination, a valve mechanism including a valve seat, a valve element cooperating with said seat, a valve seating spring, and a guard, said guard providing a recess for receiving said valve when the latter is unseated to the maximum degree, and means associated with said recess for subjecting the side of said valve towards said recess to a subatmospheric pressure when said valve is in said recess.

25 16. In combination, a valve mechanism including a valve seat, a valve element cooperating with said seat, a valve seating spring, and a guard, said guard providing a recess for receiving said valve and a deeper recess for receiving said spring, and unloading means including means associated with said recesses for subjecting the side of said valve towards said first mentioned recess to a subatmospheric pressure when said valve is in said first mentioned recess.

30 17. In combination, a discharge valve mechanism including a valve seat, a valve element cooperating with said seat, a valve seating spring, and a guard, said guard providing a recess for receiving said valve, and unloading means including means associated with said recess for subjecting the side of said valve towards said recess to atmospheric pressure when said valve is in said recess.

35 18. In combination, a discharge valve mechanism including a valve seat, a valve element cooperating with said seat, a valve seating spring, and a guard, said guard providing a recess for receiving said valve, and unloading means including means associated with said recess for subjecting the side of said valve towards said recess to a pressure less than discharge pressure when said valve is in said recess.

40 19. In combination, a valve mechanism including a valve seat, a valve element cooperating with said seat, a valve seating spring, and a guard, said guard providing a recess for receiving

5 said valve, a deeper recess for receiving said spring, and an intermediate recess, and means associated with said last mentioned recess for subjecting the side of said valve towards said recess to a subatmospheric pressure when said valve is in said first mentioned recess.

10 20. In combination, a valve mechanism including a valve seat, a valve element cooperating with said seat, a valve seating spring, and a guard, said guard providing a recess for receiving said valve, a deeper recess for receiving said spring, and an intermediate recess, and means associated with said last mentioned recess for producing therein a pressure less than the pressure whose flow said valve controls and for subjecting the side of said valve towards said recess to such lower pressure, when said valve is in said first mentioned recess.

15 21. In a compressor controlling system, a compressor having valve mechanism including an inlet valve, means associated therewith for subjecting said inlet valve to subatmospheric pressure conditions to maintain the same open to effect unloading, means for creating a subatmospheric pressure during running of the compressor, and means for controlling the connection of said first mentioned means with said means for creating a subatmospheric pressure, controlled by compressor discharge pressure.

20 22. In a compressor controlling system, a compressor having valve mechanism including an inlet valve, means associated therewith for subjecting said inlet valve to subatmospheric pressure conditions to maintain the same open to effect unloading, a vacuum pump driven with the compressor for creating a subatmospheric pressure during running of the compressor, and means for controlling the connection of said first mentioned means with said vacuum pump, controlled by compressor discharge pressure.

25 23. For use in a valve mechanism which includes a valve seat, a valve guard, a valve between the seat and guard, and a valve seating spring, a valve guard comprising a plate having an annular groove to receive an associated valve, a narrower deeper annular groove having directly communicating therewith means for venting pressure from the space therein at the side of said valve opposite said valve seat to a lower pressure point, and a still narrower and deeper annular groove to position a spring for pressing said valve toward said valve seat.

30 24. For use in a valve mechanism which includes an annular valve seat, a guard, a circular valve and an annular spring, a valve guard comprising a plate having a groove to receive a valve in a position with its outer surface flush with the grooved face of said guard, a concentric narrower deeper groove having directly communicating therewith means for venting pressure from the space therein at the side of said valve opposite said valve seat to a lower pressure point, and a still narrower and deeper concentric groove to position a spring for pressing the valve toward the valve seat.

35 25. For use in a valve mechanism which includes an annular valve seat, a guard, a circular valve and an annular spring, a valve guard comprising a plate having a groove to receive an associated valve, a concentric narrower deeper groove having means directly associated therewith for venting pressure from the space therein at the side of said valve opposite said valve seat to a lower pressure point, and a still narrower and deeper concentric groove to position an as-

sociated spring, the mean radii of said several grooves being substantially equal.

26. In combination, in a pump, a valve mechanism including a valve movable between a guard and a seat during loaded pump operation, and means associated with said valve guard for subjecting the valve on one side thereof to the pressure of the fluid controlled by said valve to effect loaded pump operation, or to a lesser pressure to effect unloaded pump operation.

27. In combination, in a pump, a valve mechanism including a valve movable between a guard and a seat during loaded pump operation, and pump-discharge-pressure-controlled means associated with said valve guard for subjecting the valve on one side thereof to the pressure of the fluid controlled by said valve to effect loaded

pump operation, or to a lesser pressure to effect unloaded pump operation.

28. In combination, in a pump, a valve mechanism including a valve seat, a valve cooperating with said valve seat and movable to open position by a pressure-differential created during each cycle of loaded pump operation, a valve guard having a chamber to receive said valve in its open position, and means controlled by pump discharge pressure for automatically connecting said valve guard chamber to the pressure of the fluid controlled by said valve to permit normal operation of said valve, or to a lesser pressure to hold said valve in said chamber and thereby effect unloaded pump operation.

MARSHALL E. JENNINGS.

CERTIFICATE OF CORRECTION.

Patent No. 2,213,248.

September 3, 1940.

MARSHALL E. JENNINGS.

It is hereby certified that error appears in the printed specification of the above numbered patent requiring correction as follows: Page 6, second column, line 58, claim 24, after "guard" and before the comma insert the words --when said valve is in open position--; and that the said Letters Patent should be read with this correction therein that the same may conform to the record of the case in the Patent Office.

Signed and sealed this 15th day of October, A. D. 1940.

Henry Van Arsdale,
Acting Commissioner of Patents.
